[57] CLAIM

The ornamental design for an eyeglass display hanger, as shown and described.

DESCRIPTION

FIG. 1 is a perspective view of an eyeglass display hanger showing my new design;

FIG. 2 is a front elevational view thereof, the rear side being a mirror image thereof;

FIG. 3 is a top plan view thereof;

FIG. 4 is a side elevational view thereof with the opposite side being a mirror image; and,

FIG. 5 is a bottom plan view thereof.

The portions shown in broken lines are for information only and form no part of the instant design.

FIG. 3

FIG. 4

FIG. 5
